UNITED STATES PATENT OFFICE.

CHARLES A. SWANSON, OF LOS ANGELES, CALIFORNIA.

STUFFING-BOX FOR OIL-WELL PUMPS.

1,245,286.

Specification of Letters Patent.

Patented Nov. 6, 1917.

Application filed December 29, 1916. Serial No. 139,676.

To all whom it may concern:

Be it known that I, CHARLES A. SWANSON, a citizen of Sweden, residing at Los Angeles, in the county of Los Angeles and State of California, have invented new and useful Improvements in Stuffing-Boxes for Oil-Well Pumps, of which the following is a specification.

My invention relates to a lubricator stuffing box for pumping rods of oil wells.

In the ordinary construction of deep well oil pumps a stuffing box is located above the upper end of the well casing in which the pumping rod reciprocates. The flow of oil is usually subjected to fluctuations. When a pocket of gas is liberated at the bottom of the well a body of oil will be forced upwardly in the pump casing and past the stuffing box and will over-flow the upper end of the oil pump. The oil dripping over the connections and parts situated below keeps the parts greasy with oil and is a source of annoyance. At other times the yield of oil will be insufficient to form a film of oil about the pumping rod and the packing material in the stuffing box will become hot and rapidly worn because of the lack of lubrication of the pumping rod reciprocated therein.

It is the object of this invention to provide simple and positive means for insuring constant lubrication of the pumping rod and at the same time avoiding the objectionable spilling of oil on the pump connections and other parts above referred to and to carry away the surplus oil coming from the oil well through the stuffing box.

My invention comprises a closed oil chamber located immediately above the stuffing box and is designed to collect the oil which at times is forced past the stuffing box and to supply the same gradually to the pump rod for lubrication during those periods when that section of the pump rod would ordinarily lack lubrication. An over-flow pipe is provided conveying the surplus oil from the oil chamber to a drip-pan beneath, thereby avoiding any fouling of the pumping apparatus with oil.

Another object of this invention is to provide means which are exceedingly simple, easily installed and removed for repairs or cleaning purposes.

Other objects will appear hereinafter.

The accompanying drawings illustrate

the complete embodiment of my invention in which:

Figure 1 is an elevation, partly in section, of a pump casing to which my invention is applied.

Fig. 2 is a top plan view thereof.

On the upper part of the well casing 10, an internally threaded tubular coupling member 11 is screwed, which supports the lower stuffing box member 12. The latter is provided with an externally threaded neck 13 engaging the internally threaded bore of the coupling member 11. The lower stuffing box member 12 is provided with a tubular externally threaded neck 15 adapted to receive the upper tubular stuffing box member 16 which is internally threaded and adapted to engage the neck 15 of the lower stuffing box member. Integral with the upper stuffing box member 16 is a cylindrical oil chamber 17 whose upper end is closed by means of an apertured screw cap 18. A cylindrical pumping rod 19 is reciprocably mounted in the pump casing 10 and passes centrally through the tubular member 11, the stuffing box members 12 and 16, the oil chamber 17, and the screw cap 18. The adjacent ends of the stuffing box members are provided with an enlarged bore, thereby forming an annular retaining shoulder 20 in the lower stuffing box member 12 and an annular shoulder 21 in the upper stuffing box member 16. In the stuffing box is an annular chamber 22. Surrounding the rod 19 a packing material is provided which may consist of rings of rubber 23, hemp or any other suitable packing material and is held firmly in position by means of upper and lower packing sleeves 24 and 25. The pressure exerted by these packing sleeves on the packing material can be adjusted by screwing the upper stuffing box member upon the neck 15, as will be understood.

An over-flow pipe 26 is provided leading from the upper part of the oil chamber 17, the lower end thereof being vertically above an open cylindrical drip-pan 27, whose bottom is provided with a screw threaded aperture 28 secured on neck 29 of the tubular member 11. An outlet pipe 30 leads from the drip-pan 27 to any convenient oil collecting means, (not shown).

The upper stuffing box member 16 which carries integrally therewith the oil chamber 17 is provided with a pair of oppositely dis-

posed internally threaded nipples 31 for the reception of externally threaded rods (not shown) whereby the stuffing box member and oil chamber may be removed or adjusted 5 in relation to the lower stuffing box member. The lower stuffing box member 12 is provided with a hexagonal neck 32 whereby the same may be engaged by a wrench for screwing and unscrewing the same in position.

10 The operation of the lubricating device is as follows:

Whenever the oil well flows freely and the pumping rod 19 carries a film of oil above the stuffing box into the oil chamber 17, the 15 surplus oil is collected in said chamber, which acts as an oil reservoir. This is especially the case when a pocket of gas is encountered at the bottom of the well which forces oil between the packing and the 20 pumping rod into the oil chamber. During the period when the pumping rod would normally run dry and be without lubrication the oil chamber 17 would supply oil to said rod, thus keeping the same lubricated and 25 avoiding the bearing from becoming hot, thus preserving the life of the packing. When the level of oil in the oil chamber 17 rises to the outlet pipe the excess oil will 30 over-flow therethrough and drip into the drip-pan 27 situated beneath said pipe, whence the same is conducted through the outlet pipe to any convenient collecting means. The drip-pan will also catch the leakage through the threads and joints of 35 the stuffing box.

It is thus seen that I have devised a simple, yet efficient lubricator for the pumping rod which utilizes the excess oil forced and carried past the stuffing box for lubrication.

In case the oil supply in the oil chamber 40 should run low the packing may be loosened by unscrewing the top to allow the oil to flow into the chamber and fill the same. It is good practice to partly fill the oil chamber with a heavy grease or with tallow to 45 be mixed with the oil of the well in order to provide a lubricant having a greater viscosity.

While I have shown my preferred embodiment of the invention it will be obvious 50 to those skilled in the art that various changes in the details and construction thereof may be resorted to without departing from the spirit of my invention as 55 claimed.

I claim:

A stuffing box for oil well pumps comprising a coupling adapted to connect with the oil well casing and having a central bore for the pump rod, a lower stuffing box member connected to the coupling, an upper stuffing box member connected to the lower member, a cylindrical body formed integral with the upper stuffing box member concentric with the pump rod and forming an 60 oil chamber, a cap for closing the chamber, an overflow pipe leading from the top of the chamber, a drip-pan connected to the coupling and surrounding the lower part of the stuffing box; said overflow pipe discharging 65 into the drip-pan; and a drain for the drip pan; so as to carry off surplus oil passing 70 upwardly from the oil well through the stuffing box.

In testimony whereof I have signed my 75 name to this specification.

CHAS. A. SWANSON.
